S. R. BRICK.
GAS BURNER.
No. 9,742. PATENTED MAY 24, 1853.

UNITED STATES PATENT OFFICE.

SAMUEL R. BRICK, OF PHILADELPHIA, PENNSYLVANIA.

IMPROVEMENT IN GAS-BURNERS.

Specification forming part of Letters Patent No. 9,742, dated May 24, 1853.

To all whom it may concern:

Be it known that I, SAMUEL R. BRICK, of Philadelphia, in the county of Philadelphia and State of Pennsylvania, have invented an Improvement in Gas-Burners, of which the following is a specification.

The nature of my invention consists in providing the interior of the ordinary gas-burner with a long center conducting-pipe surrounded by a long concentric capping pipe, causing the gas to be suddenly deflected from the top of the conducting pipe and to descend, and thus have its pressure diminished, and afterward pass through horizontal perforations in the base of the capping-pipe into the area of the burner and ascend to the burning-point, by which means the supply for burning is made uniform, though the pressure in the main gas-pipes may vary, and blowing of the gas and waste is thereby prevented and good combustion and a steady bright light is obtained.

To enable others skilled in gas fitting to make and use my invention, I will proceed to describe its construction and action, reference being had to the annexed drawings, making part hereof; and to make the philosophical principles on which the invention is based more clearly understood, I will state the facts: first, that gas, (like all fluids,) when passing through long small apertures, is subject to some friction, which tends to diminish its velocity and pressure and tends to make the supply at the burning-point uniform; second, that a sudden deflection of gas checks its velocity and tends to make its pressure and supply at the burning-point uniform; third, that gas, being lighter than the common atmosphere, has always a strong tendency to rise, and hence causing it to descend tends to make its pressure and supply at the burning-point uniform; fourth, that passing gas through holes whose combined area is smaller than those holes or the aperture at the burning-point tends to prevent an excessive supply and to make the supply uniform at the burning-point.

The object of my invention is to make the flow of gas at the burning-point uniform and not excessive, notwithstanding a variation of pressure in the main gas-pipes, on the combined principles operating in the same suc-

sive order and by the combined means herein set forth.

Figure 1 is a sectional view through the middle of the entire burner. Fig. 2 is a perspective view of the ordinary burner with the improvement applied to it. In both of which like letters refer to like parts.

In Fig. 1, *a* is the common gas-burner screwed on a male screw at the base of the center conducting-aperture, *b*, which center pipe has a lower female screw-base, *c*, which screws onto the supply gas-pipe. This center conducting-pipe is made as long as possible, and the aperture in it is about one-sixteenth of an inch in diameter, to retard the velocity of the gas. Over this center conducting-pipe, on a male screw near its base, I screw a concentric capping-pipe, *e*, also as long as possible, and having a small space above and a deep space around the conducting friction-pipe and small horizontal perforations *d d*, near the base of this deep space, communicating from it through the capping-pipe to the area of the burner or outer tube, in order that the gas shall be suddenly deflected from the top of the center conducting pipe and then descend as much as possible and afterward be drawn by the small perforations through the base of the capping-pipe as it escapes into the common burner and ascends to the burning-point, by which means the slight friction, sudden return or deflection, descent, and drawing of the gas, in the order presented, may make the supply at the burning-point uniform, though the pressure in the main pipes varies, and the blowing and waste of gas is prevented and a most complete combustion and bright light is obtained.

I do not claim passing the gas through a small long aperture, nor a sudden deflection of it, nor a descent of it, nor drawing it, nor any of them together, less than the whole.

What I do claim, and desire to secure by Letters Patent, is—

The arrangement and combination of the center conducting-pipe and its capping-pipe inside of the common gas-burner, in the manner and for the purposes above described.

SAM. R. BRICK.
